UNITED STATES PATENT OFFICE

WILLIAM WALLACE SPIERS, OF LONDON, ENGLAND

BINDER FILE

Application filed October 19, 1927, Serial No. 227,088, and in Great Britain November 10, 1926.

My invention relates to files for binding a plurality of sheets or papers together, whereby they may be easily turned over for inspection, or one of them or a batch of them may be readily removed when required.

A file embodying the invention comprises a support, a member pivotally mounted on the support and having detachable posts upon which the sheets or papers are carried, a device for clamping the sheets or papers in position, the clamping device comprising a bar provided with strips of material on said bar for saving the sheets from damage by tearing by the posts.

The elements comprising my file may be variously constructed and assembled to meet the particular service as will be evident from the file I will now describe, by way of example, with reference to the accompanying drawings, and suitable for sheets typifiable by stock exchange lists and newspapers.

Of these drawings:

- 25 Fig. 1 is a plan;
 Fig. 2 is a side elevation;
 Fig. 3 is an end elevation;
 Fig. 4 is a plan of a detail hereafter referred to; and
 30 Fig. 5 is a fragmentary elevation of a modification also referred to hereinafter.

The same letters of reference are adopted to denote the same parts throughout.

According to this form, I employ a backing *a* of stiff material, and of rectangular shape. The corners, or some of the corners, of the backing may be strengthened in any usual or suitable fashion as indicated at *b*, while for providing for easy movement over 35 a table or other support and to obviate scratching, the outer face of the backing *a* may be fitted with a runner *c* or runners of appropriate kind, such as, as represented, of the domed-disc variety.

- 45 At one side or edge of the backing *a* I secure a bracket *d* in the form of a flat plate *e* having its ends turned up at right angles to the body portion to form lugs *f*, *f* for the pivotal supporting of a detachable bar *g*.
 50 The bar *g* may be pivotally mounted in any

convenient way; for instance, the bar *g* may have a screw-threaded boring at each end for the reception of a screw-stud *h* having an intermediate circular portion or neck *i*, this circular portion or neck *i* turning in the lug *f* on the assemblage of the stud *h* with the bar *g* and constituting the pivot to the bar *g*. Intermediate of its ends the bar *g* is provided with two or more detachable posts *j*, *j* in spaced relation. Suitably, each post *j* is screw-threaded throughout, and one of its ends is inserted into a corresponding hole provided in the bar *g*, while the other end is furnished with a removable nut *k*, knurled or otherwise adapted for convenient manipulation. These posts *j*, *j* are for the reception of the sheets or the like to be filed, which are perforated for the purpose. Thus the bar *g* and posts *j*, *j* constitute a carrier for the sheets.

The extreme end *l* of each post *j* remote from its bar *g* is of square or polygonal formation for the reception of a corresponding key *m*, such as that represented in Fig. 4, so that the post *j*, with its associated nut *k*, may be quickly detached from the bar and re-attached.

A perforated bar *n* is furnished for threading over the posts *j*, *j* and clamping the sheets likewise threaded over the posts *j*, *j* for filing, and strips *o*, *o* of flexible material are connected to it for functioning as protectors to the sheets relatively to the posts *j*, *j*.

For use, the carrier bar *g* is mounted in the bracket *d* on the backing *a* with the posts *j*, *j* attached thereto, but with the nuts *k*, *k* and the clamping bar *n* removed. Then the sheets, which have been previously punched in a usual way in agreement with the posts *j*, *j*, (or in the way described in the specification of my corresponding United States application, Serial No. 227,752 for a perforator) are threaded over the posts *j*, *j* and likewise the clamping bar *n*, whereupon the nuts *k*, *k* are applied to tightly bind the sheets between the clamping bar *n* and the carrier bar *g*.

The sheets can be examined by turning them book-fashion which is permitted by the

100

rotation of the carrier bar *g* and the clamping bar *n* with it, during which operation the strips *o*, *o* interpose themselves between the posts *j*, *j* and the sheets, thereby saving the sheets from damage by tearing or otherwise. Now, supposing it is desired to detach the first-mentioned or undermost sheets, the posts *j*, *j* are detached by the key *m* applied at their square or polygonal ends, *l*, *l*, whereupon the sheets can be removed and the posts *j*, *j*, with the remaining assembled sheets, reapplied, when the whole is ready for re-use.

Similarly, any other intermediate sheet or sheets can be displaced and replaced by another; while to add a new sheet on the top of the pile of assembled sheets it is only necessary to remove the nuts *k*, *k* and clamping bar *n* and then reapply them over the new sheet.

20 Instead of the ends *l*, *l* of the posts *j*, *j* being adapted for the reception of the key *m*, they, as depicted in Fig. 5, may be of normal formation and provided with a hole for the reception of a "tommy" pin *p*.

25 Again, instead of the posts *j*, *j* being of single formation, they may be constructed in sections in well-known fashion to permit of building up to meet the growth of the pile of sheets.

30 The various parts mentioned may be of any appropriate material, but, suitably, the backing *a* is of cardboard or the like, the bracket *d*, the bar *g*, the screw-stud *h*, the post *j*, the nut *k*, the key *m* and the bar *n* are of metal, 35 and the strip *o* is of leather.

In the example, it will be understood that the backing *a* constitutes the main support of the file, whereas, in other forms, the bracket *d* may be adopted as the support, i. e., the backing *a* may be dispensed with.

40 What I claim and desire to secure by Letters Patent is:

1. A binder file comprising a backing, a bracket secured to the backing, a bar pivotally mounted in the bracket, posts detachably connected to the bar, a clamping bar removably combined with the posts, nuts associated with the posts and the clamping bar, and means whereby the extreme ends of the posts 45 remote from the bar are adapted for the reception of a device for removing and replacing the posts.

2. A binder file comprising a support, a member pivotally mounted on the support and having detachable posts upon which the sheets or papers are carried, a device for clamping sheets or papers in position, the clamping device comprising a bar provided with strips of material adapted to lie between the sheets 50 or papers and posts for saving the sheets from damage by the posts when the sheets or papers are open.

60 3. A binder file comprising a backing, a bracket secured to the backing, a bar pivotally mounted in the bracket, posts detachably

connected to the bar, a clamping bar removably combined with the posts, nuts associated with the posts and the clamping bar, the clamping bar being provided with strips of material adapted to lie between the sheets or 70 papers and the posts for saving the sheets from damage by the posts when the sheets or papers are open.

4. A binder file comprising a support, a member pivotally mounted on the support 75 and having posts upon which sheets or papers are carried, a device for clamping the sheets or papers in position, the clamping device comprising a bar provided with strips of material adapted to lie between the sheets or 80 papers and the posts for saving the sheets from damage by the posts when the sheets or papers are open.

5. A binder file comprising a backing, a bracket secured to the backing, a bar pivotally mounted in the bracket, posts connected to the bar, a clamping bar removably combined with the posts, nuts associated with the posts and the clamping bar, the clamping bar being provided with strips of material adapted to lie between sheets and posts for saving 85 the sheets from damage by the posts when the sheets are open.

6. A binder file comprising a support, a member pivotally mounted on the support 95 and having detachable posts upon which the sheets or papers are carried, said posts being screwed to said pivoted member, a device for clamping the sheets or papers in position, the clamping device comprising a bar provided 100 with strips of material adapted to lie between the sheets or papers and the posts for saving the sheets from damage by the posts when the sheets or papers are open.

In testimony wherof, I affix my signature. 105
WILLIAM WALLACE SPIERS.
